Fig. 6

FIG. 1 is a top plan view of a fish lure showing my new design;

FIG. 2 is a side elevational view;

FIG. 3 is an end view of the left end of FIG. 2;

FIG. 4 is an end view of the right end of FIG. 2;

FIG. 5 is a rear side elevational view; and

FIG. 6 is a transverse sectional view taken along section line 6—6 of FIG. 5.

The entire side surface areas, except for the portion enclosed by the scalloped edge and the parallel lines, are covered with reflective material. The portion of the body between the parallel lines is transparent and the scalloped edge portion is of contrasting color. The dotted line showing of the hook and mounting therefor is for the purpose of illustration only.

I claim:

The ornamental design for a fish lure, as shown and described.
